Primary Examiner — Calvin E Vansant*Assistant Examiner* — Benjamin L. Gray(74) *Attorney, Agent, or Firm* — Akerman LLP;
Alejandro J. Fernandez(57) **CLAIM**

The ornamental design for a cabinet handle cover, as shown and described.

DESCRIPTION

FIG. 1 is a perspective front view of a cabinet handle cover showing my new design;

FIG. 2 is a perspective rear view of thereof;

FIG. 3 is a top view of thereof;

FIG. 4 is a bottom view thereof;

FIG. 5 is a left side view thereof;

FIG. 6 is a right side view thereof;

FIG. 7 is a front view thereof;

FIG. 8 is a rear view thereof;

FIG. 9 is a left perspective view thereof;

FIG. 10 is a front view thereof in an environment of use;

FIG. 11 is a perspective rear view thereof separate from a handle; and,

FIG. 12 is another perspective rear view thereof covering a handle.

In all figures, broken lines illustrate environmental structures and form no part of the claimed design.
